SAFETY DEVICE TO PREVENT FREE FALLS

Robert C. Gschwind, Chicago, Ill.

Application May 24, 1955, Serial No. 36,184

Term of patent 3½ years

(Cl. D41—1)

Fig. 1 is a perspective view of a safety device to prevent free falls showing my new design; and

Fig. 2 is a side elevational view thereof.

The back is substantially plain.

The rope portion is shown for purposes of illustration only.

I claim:

The ornamental design for a safety device to prevent free falls, as shown and described.
